UNITED STATES PATENT OFFICE.

JAMES D. PETTIT, OF BURLINGTON, IOWA.

COAL-CHUTE.

SPECIFICATION forming part of Letters Patent No. 252,055, dated January 10, 1882.

Application filed August 3, 1881. (No model.)

To all whom it may concern:

Be it known that I, JAMES D. PETTIT, a citizen of the United States, residing at Burlington, in the county of Des Moines and State of Iowa, have invented certain new and useful Improvements in Coal-Chutes; and I do hereby declare the following to be a full, clear, and exact description of the invention, such as will enable others skilled in the art to which it applies:

10 pertains to make and use the same, reference being had to the accompanying drawings, and to letters or figures of reference marked thereon, which form a part of this specification.

This invention relates to improvements in 15 coal-chutes of that class used for loading coal into locomotive-tenders; and the invention consists, first, in a box or chute mounted in a frame in such manner that when loaded with coal it will by gravity slide forward so as to 20 bring its discharge end over the tender, and may be returned after discharging its coal by counter-weights, springs, or other devices.

The invention further consists in a catch 25 adapted to hold the gravitating chute in its position when loaded, and also in its position when unloaded.

The invention further consists in constructions and combinations hereinafter described, and set forth in the claims hereto annexed.

30 In the accompanying drawings, which illustrate my invention, and in which the same reference-letter indicates the same part in the different figures, Figure 1 is a perspective. Fig. 2 is a side elevation. Fig. 3 is a top plan. Fig. 35 4 is an end elevation of chute.

Referring to the drawings by letters, letter A represents a frame, which may be of any desired construction that will support bars B B' at each of its sides, which bars are somewhat 40 lower at one end than their other end and form the track for the chute to run upon, as hereinafter described.

C is the chute, having sides C', end or door C'', and bottom C''', which descends or inclines 45 toward the end C''. The bottom C''' preferably extends slightly beyond the end C'', and has side boards, C''', on its projecting end. The end C'' is hinged at its upper end, so that its lower end may swing outward, as shown by 50 dotted lines at Fig. 2. D D' are gravitating latches pivoted at d d', respectively, the outer

ends of which latches drop by gravity into notches d'' in the side boards, C''', and hold the door C'' in a closed position. The inner end of the latch D' rests upon the adjacent end 55 of the latch D, so that raising the outer end of the latch D' to release it from the notch in the side board will also raise the outer end of the latch D and release it, as shown by dotted lines at Fig. 4.

E is a gravitating catch, pivoted at one end to the outer end of the latch-bar D', and projects forward through a slot in a bar, e, of the chute. When the door C'' is open a shoulder or notch, e, on the catch E will engage with a 65 catch, e', on the bar e and hold it open, as shown by dotted lines at Fig. 2.

An upper bar, B, is located on each side of the frame A, and wheels F, one on each side of the chute, and near its upper rear end, are 70 adapted to run on the bar B, while similar wheels, F', support the forward end of the chute and run on the bars B'.

G G are pulleys carried on a shaft, H, which is journaled in suitable bearings near the rear 75 end of the frame A. Cords or chains I, attached to the bottom of the chute A, extend over the pulleys G and carry counterpoise weights I' on their rear ends. The weight of the counterpoises I' should be such that when the chute or 80 car C is unloaded the counterpoises will be heavy enough to draw the car back to the position shown by dotted lines at Fig. 2.

J is a guide-bar, fixed to the side of the chute or car C, and has a notch, j, at its front end 85 and a notch, j', at its rear end.

K is a latch-bar, pivoted near its mid-length portion to a standard, L, which projects from the frame A. The rear end, K', of the bar K is the heavier, and is turned inward and rests 90 on its guide-bar J, so that when the chute C is drawn back, as shown by dotted lines at Fig. 2, the end K' will fall into the notch j' and hold the chute in said position. The forward end of the latch K carries a hand-hold rod, M, which 95 may be drawn downward to raise and release the end K' from either notch j or j'.

N is a stop, against which a wheel, F, strikes to limit the movement of the chute forward, and N' are stops which strike the frame A to limit 100 its movement rearward. The stops N' are also projected over the projecting end of the track-

bar B', as shields to protect it from the coal which may fall thereon.

In operation the chute, when empty, stands in the position shown by dotted lines at Fig. 2, where it is held, as hereinbefore described. While in this position it may be filled with coal. The frame A is located near the railway-track, so that the locomotive tender may be brought near to the discharge end of the chute, when by pulling down on the rod M the latch K' will be released from the notch j, and the weight of the coal overcoming the weight of the counterpoises I', the chute will run forward on its wheels F F' to the position shown by full lines at Figs. 1 and 2, with its discharge end projecting into the upper open side of the tender. The latch-bar D' may now be raised, as hereinbefore described, to release the door C'', when the coal will force it outward, and sliding down the inclined bottom C''' will be discharged into the tender. The coal in escaping will force the door C'' outward until the latch E engages with the catch e to hold it open, as hereinbefore described. When the coal has escaped from the chute the latch E may be raised slightly to release it and allow the door C'' to close by its own gravity, the latches D D' sliding up over the inclined sides of the side boards, C''', and engaging with their respective notches therein. When the chute was run forward by the gravity of the coal, as last described, the latch K' slid along on the guide-bar J until the chute struck the stop N, when the latch K dropped into the notch j', where it engages so as to hold the chute in its outward position when unloaded, and until the latch K' is raised, as hereinbefore described, and permits the counterpoises I' to draw the chute back and ready for again filling and discharging, as hereinbefore described. It will be seen that the gravitating chute may be used for delivering coal to vessels or other receivers.

What I claim as new is—

1. In combination with a frame in which it is mounted, a coal chute adapted to be carried forward and project from the frame over a locomotive tender or receiver by means of the force of gravity of the loaded chute. 45
2. The combination, with the gravitating chute or box and supporting-frame, of a latch, K, and catch j', for holding the chute in a position projected from the supporting-frame, substantially as and for the purpose specified. 50
3. In combination with the supporting-frame and gravitating chute, having counterpoise weight I', and guide-bar J, having notches j j', the gravitating latch K, adapted to engage the notches j j' and to slide upon the bar J, substantially as and for the purpose specified. 55
4. In combination with the gravitating chute, having a bar, J, fixed thereto, with notches j j' in its ends, a latch, K, adapted to engage said notches, substantially as and for the purpose specified. 60
5. In combination with the chute C and hinged door C'', the latches D D', adapted to engage the side boards, C''', to hold the door C'' closed, and their adjacent ends overlapped, so that raising the outer end of one will release it and also act upon the other to release it, 70 substantially as and for the purpose specified.
6. In combination with the chute, hinged door, and latches D D', the gravitating latch E, hinged to one of the latches, D or D', and adapted to engage a catch on the side of the chute, substantially as and for the purpose specified. 75

In testimony whereof I affix my signature in presence of two witnesses.

JAMES D. PETTIT.
